DETERGENT COMPOSITIONS

Jay C. Harris, Dayton, Ohio, assignor to Monsanto Chemical Company, St. Louis, Mo., a corporation of Delaware

No Drawing. Application November 23, 1948,
Serial No. 61,739

5 Claims. (Cl. 252—140)

1

This invention relates to detergent compositions suitable for washing textiles and for other purposes. It relates particularly to detergent compositions which may be used in automatic washing machines which are constructed in whole or in part of vitreous enameled steel or of aluminum.

In an earlier copending application in the name of Milton Kosmin, Serial No. 718,133, filed December 23, 1946, which application is assigned to the same assignee as is the present case, there is disclosed the condensation products of tertiary mercaptans having from 6 to 20 carbon atoms with ethylene oxide. The tertiary mercaptans are preferably derived from polymerized olefins, as described in U. S. Patent No. 2,392,555. As described in the above-entitled pending application, the condensation product may be produced so as to contain as much as 40 moles of ethylene oxide per mole of mercaptan. For detergent purposes, however, condensation products containing from 5 moles to 20 moles of condensed ethylene oxide per mole of mercaptan are preferred.

For the production of detergent compositions employing the tertiary mercaptan-ethylene oxide condensation product as the active ingredient, it has also been proposed in the above copending application that the composition contain alkali metal phosphates. Suitable phosphates may consist of a sodium tripolyphosphate,

$\text{Na}_5\text{P}_3\text{O}_{10}$

or tetrasodium pyrophosphate, $\text{Na}_4\text{P}_2\text{O}_7$, or fused or sintered products approximating these compositions or mixtures thereof. It is also possible to incorporate in the composition other inorganic water-soluble salts, such as sodium carbonate, sodium bicarbonate, sodium sesquicarbonate, as well as sodium sulfate, sodium borate, etc.

I have now found that when such compositions, as above mentioned, are employed in automatic laundry devices, such as household washing machines, constructed in whole or in part of aluminum or of vitreous enameled steel, the surfaces of these devices which are exposed to contact with detergent solutions are etched or corroded so as to lead to an undesirable roughening of the surfaces so exposed and in some cases to failure of the vitreous coating.

I have further found that substantially complete protection can be obtained by including in the detergent compositions from 10% to 25% by weight of a solid sodium silicate, wherein the $\text{Na}_2\text{O} : \text{SiO}_2$ mole ratio is between 1:2 and 1:3.2,

2

The percentage of the silicate stated above is based upon the anhydrous form. The liquid form of sodium silicate known as "water glass" should not be employed because of its adverse effect on the product. The phosphates and the carbonates in the composition may be in the hydrated or anhydrous form; however, when water of hydration is present allowance should be made for the amount present in order to maintain the ingredients when dissolved in water within the range disclosed and claimed.

The present compositions should also contain alkaline builders such as tetrasodium pyrophosphate or the sodium tripolyphosphate, $\text{Na}_5\text{P}_3\text{O}_{10}$, sodium carbonate, sodium bicarbonate, or mixtures of these salts in the proportions stated. Starch may be present in the amount stated. The $\text{Na}_2\text{O} : \text{SiO}_2$ ratio of the sodium silicates employed should be held within the limits stated so that the solid silicates will dissolve in the detergent solution at a rate sufficiently rapid so that they will be effective for corrosion prevention from the instant of solution of the detergent. They should, moreover, be employed in the amount stated, since I have found that quantities below the lower limits stated above are ineffective for the purpose, while quantities above the upper limit are undesirable, because of an adverse effect upon the detergative efficiency of the composition.

The composition of my present detergent product, together with the range of ingredients effective for the present purpose is as follows, all parts being by weight and based on the anhydrous ingredients:

	Parts
Condensation product of a tertiary mercaptan with 6-20 carbon atoms with from 5 to 20 moles of ethylene oxide per mole of mercaptan	15-25
40 Tetrasodium pyrophosphate or sodium tripolyphosphate	20-60
Sodium silicate (anhydrous) $\text{Na}_2\text{O} : \text{SiO}_2$ ratio of 1:2 to 1:3	10-25
45 Starch	0-20
Alkaline material selected from the class consisting of sodium carbonate, sodium bicarbonate and mixtures thereof	10-25
Carboxy methyl cellulose	0.5-5
Total to give 100 parts of detergent composition.	
For washing soiled textiles, the above composition is dissolved in hot water to give preferably a 0.1% solution, although other concentrations may also be employed.	

The following more specific examples illustrate this invention:

Example 1

A composition consisting of an intimate mixture of the following ingredients is prepared, the proportions being based on the anhydrous salts:

	Parts
Condensation product of one mole of tertiary dodecyl mercaptan with 10 moles of ethylene oxide	20
Tetrasodium pyrophosphate	40
Sodium carbonate	24
Sodium silicate, $\text{Na}_2\text{O} : \text{SiO}_2 = 1:2$	15
Carboxy methyl cellulose	1
Total	100

The above composition was prepared by adding the mercaptan-ethylene oxide condensation product in liquid form to finely divided tetrasodium pyrophosphate in a mixing device and then adding the sodium carbonate, the sodium silicate, and the carboxy methyl cellulose. The order of addition is not critical. The ingredients, all of which are in finely divided form, may be added in any desired order.

Example 2

	Parts
Condensation product of one mole of tertiary dodecyl mercaptan with 15 moles of ethylene oxide	20
Tetrasodium pyrophosphate	40
Sodium carbonate	15
Sodium silicate (anhydrous), $\text{Na}_2\text{O} : \text{SiO}_2 = 1:3.2$	10
Starch	14
Carboxy methyl cellulose	1
Total	100

Example 3

	Parts
Condensation product of one mole of tertiary tetradecyl mercaptan with 20 moles of ethylene oxide	20
Tetrasodium pyrophosphate	40
Sodium sesquicarbonate	18
Sodium silicate, $\text{Na}_2\text{O} : \text{SiO}_2 = 1:2$	20
Carboxy methyl cellulose	2
Total	100

The above compositions provide maximum detergency without noticeable corrosive action upon vitreous enamel or upon aluminum washer bas-kets.

The amount of sodium silicate employed should comprise at least 10% and not in excess of 25% of the detergent composition. Within the above limits the product does not absorb excessive amounts of moisture from humid air under conditions ordinarily encountered in the use of the detergent. The detergent remains free flowing, exhibiting no tendency to cake due to the silicate present.

What I claim is:

1. A detergent composition consisting per 100 parts thereof, of the following ingredients in parts by weight:

Condensation product of a tertiary mer-captan with 6-20 carbon atoms with from 5 to 20 moles of ethylene oxide per mole of mercaptan

15-25

Parts

A sodium phosphate selected from the class consisting of tetrasodium pyro-phosphate and sodium tripolyphosphate	20-60
5 Sodium silicate, $\text{Na}_2\text{O} : \text{SiO}_2$ ratio of 1:2 to 1:3.2	10-25
Starch	0-20

Alkaline material selected from the class consisting of sodium carbonate and sodium bicarbonate and mixtures thereof	10-25
Carboxy methyl cellulose	0.5-5

2. A detergent composition consisting of the following ingredients in parts by weight:

	Parts
Condensation product of one mole of tertiary dodecyl mercaptan with 10 moles of ethylene oxide	20
20 Tetrasodium pyrophosphate	40
Sodium carbonate	24
Sodium silicate, $\text{Na}_2\text{O} : \text{SiO}_2 = 1:2$	15
Carboxy methyl cellulose	1

3. A detergent composition consisting of the following ingredients in parts by weight:

	Parts
Condensation product of one mole of tertiary dodecyl mercaptan with 15 moles of ethylene oxide	20
30 Sodium tripolyphosphate	40
Sodium carbonate	15
Sodium silicate (anhydrous), $\text{Na}_2\text{O} : \text{SiO}_2 = 1:3.2$	10
Starch	14
Carboxy methyl cellulose	1

4. The process which comprises dissolving in water a detergent product having a composition as defined by claim 1 to form a detergent solution and then washing textiles therewith, said washing process being conducted in the presence of vitreous enameled or aluminum surfaces, whereby corrosion of said surfaces normally occurring in the absence of the sodium silicate contained in the said product is substantially prevented.

5. The process which comprises dissolving in water a detergent product having a composition as defined by claim 2 to form a detergent solution and then washing textile products therewith, said washing process being conducted in the presence of vitreous enameled or aluminum surfaces, whereby corrosion of said surfaces normally occurring in the absence of sodium silicate contained in said product is substantially prevented.
